UNITED STATES PATENT OFFICE.

CHRISTOPHER C. SHELBY, OF NEW YORK, N. Y.

SUSPENDER-BUCKLE.

SPECIFICATION forming part of Letters Patent No. 320,405 dated June 16, 1885.

Application filed April 22, 1885. (No model.)

To all whom it may concern:

Be it known that I, CHRISTOPHER C. SHELBY, of New York city, county, and State, have invented certain new and useful Improvements 5 in Suspender-Buckles; and I do hereby declare the following to be a full, clear, and exact description of the same, reference being had to the accompanying drawings, forming a part of this specification, and to the figures 10 and letters of reference marked thereon.

My invention has for its object to provide a cheap, simple, and durable buckle for suspenders that can be with facility adjusted up and down upon the webbing and securely fastened at any desired point of adjustment, and 15 constructed so as to expose no projecting metallic portions on the inner or under side of the webbing that would soil or tear the clothing of the wearer.

20 I will first describe my improved buckle, and will then point out what I deem to be its particular points of novelty in the claim at the end of this specification.

Referring to the accompanying drawings, 25 Figure 1 represents a perspective view of a buckle constructed in accordance with my invention. Fig. 2 is a longitudinal vertical section of the same applied to a piece of webbing. Figs. 3, 5, 7, and 9 are perspective 30 views of different modifications of my invention. Figs. 4, 6, 8, and 10 are respectively sectional views of the buckles shown in Figs. 3, 5, 7, and 9, and showing the manner of their 35 application to webbing. Fig. 11 is a rear view of the modification shown in Fig. 9.

Similar letters of reference in the several figures indicate like parts.

In the form of the invention shown in Figs. 1 and 2 the body A of the buckle is formed 40 substantially flat, and has a cross-bar, a, at the top, another cross-bar, b, at the bottom, and three intermediate cross bars, c d e. The cross-bar d serves as the pivot for a locking-lever, B, the connection between the two being effected by turning lugs or ears f, formed upon 45 said locking-lever, around the said cross-bar d, so as to form eyes, as shown. Near its pivot the locking-lever is provided with an inwardly-projecting clamping-jaw, g, and at its outer 50 end it is provided with means—such as a hook, h—for the attachment of the suspender-end.

In applying the buckle thus formed to the

webbing of a suspender the end of the webbing is inserted first between the cross-bars a and c, then through between c and d, then 55 between d and e, and then finally between e and b, the locking-lever B being swung up into the position shown in dotted lines Fig. 3 while this operation is being performed. After the buckle is thus applied to the webbing it 60 may be slipped to the desired point by grasping the projecting locking-lever and locked at its place of adjustment by depressing the locking-lever into the position shown in full lines Fig. 2, this movement causing the clamping- 65 jaw g to co-operate with the cross-bar e and form an abrupt bend in the webbing, which renders it impossible for the buckle to be disturbed so long as the locking-lever remains 70 turned down.

It will be observed that by reason of the connection of the suspender-end to the extremity of the locking-lever the latter is ordinarily held positively down by the weight 75 of the wearer's pantaloons, and that hence 80 there is no liability of the locking-lever becoming displaced. It will also be noted that on the inside of the buckle, or, in other words, on that side which comes next the person of the wearer, there are no projecting metallic 85 portions to tear or soil the wearer's shirt or project into his person, there being, in fact, but two portions of the buckle exposed at all on that side of the buckle—to wit, the cross-bars 90 c and e, which cross-bars are very narrow, 95 and by the bends of the webbing are set back considerably below the bearing-surfaces 100 12 3 of the webbing out of the way.

In the modifications shown in Figs. 3 and 4 the buckle frame proper is formed with but 90 three cross-bars—namely i k l—which correspond to the cross-bars c d e of the device shown in Figs. 1 and 2, while in Figs. 5 and 6 four cross-bars—viz, m, n, o, and p—are employed, and in Figs. 7, 8, 9, 10, and 11 only 95 two cross-bars are employed, the pivotal connection of the locking-lever to the buckle-frame proper being made by means of short studs or pivots q projecting from the sides 100 of the frame into the eyes formed on the locking-lever in the modification shown in Figs. 7 and 8, and by means of studs or pivots r r, formed upon the locking-lever and projecting through perforations in ears, s, formed upon

the frame, in the modification shown in Figs. 9, 10, and 11.

The clamping-jaw of the locking-lever may, if desired, be formed with teeth or serrations, 5 as shown in Fig. 11; but ordinarily I prefer to dispense with these teeth, as a sufficiently firm hold can be secured upon the webbing without the aid of them, and the liability of the webbing being torn or injured is lessened.

10 In all the modifications represented in the drawings it will be noted that the clamping-jaw of the locking-lever co-operates with the two cross-bars located on opposite sides of the pivot in the same manner, and also that 15 in all of them there is the same absence of the projecting parts of metal on the inner side, next the person of the wearer.

What I therefore claim as my invention is—
In a suspender buckle, the combination,

substantially as described, of a buckle-frame 20 having the two cross-bars and a locking-lever pivoted between them, and having the short inwardly-projecting clamping-jaw near its inner end, and having also a device—such as a hook—at its outer end for the connection of 25 the suspender-end, whereby when the buckle is applied to the webbing or body of the suspender, as described, and the locking-lever is turned down, the short clamping-jaw of the lever will co-operate with the two cross-bars 30 of the buckle-frame to securely hold the webbing, while the pull upon the outer end of the locking-lever will operate to keep said lever turned down, substantially as described.

CHRISTOPHER C. SHELBY.
